UNITED STATES PATENT OFFICE.

WILLIAM ELSWORTH JOHNSON, OF HALIFAX, NOVA SCOTIA, CANADA.

APPARATUS FOR LOADING BARRELS.

1,362,488.

Specification of Letters Patent. Patented Dec. 14, 1920.

Application filed October 30, 1919. Serial No. 334,495.

To all whom it may concern:

Be it known that I, WILLIAM E. JOHNSON, a citizen of the United States, residing at Halifax, in the county of Halifax and 5 Province of Nova Scotia, Canada, have invented certain new and useful Improvements in Apparatus for Loading Barrels; and I do hereby declare the following to be a full, clear, and exact description of the invention, such as will enable others skilled in 10 the art to which it appertains to make and use the same, reference being had to the accompanying drawings, and to the letters and figures of reference marked thereon, which 15 form a part of this specification.

This invention relates to new and useful improvements in apparatus for loading barrel packages from piers to ships' holds and affords simple and efficient apparatus for 20 preventing the crushing of bilges and forcing heads out which often occur when barrels slip out of sling in mechanism as commonly employed.

The invention consists further in the provision of an apparatus of this nature whereby barrel cargo may be loaded without the necessity of opening up all the hatches as it will be necessary only to open one of sufficient size through which a conveyer may be 25 passed, and which is considered an important factor in loading material, particularly perishable cargo during the winter season.

My invention is illustrated in the accompanying drawing in which:

35 Figure 1 is a vertical sectional view through a pier and a ship with my approved loading apparatus applied thereto.

Fig. 2 is a top plan view of the movable platform.

40 Fig. 3 is a longitudinal view through the platform.

Fig. 4 is the side elevation of part of the conveyer apparatus and shock absorber.

Fig. 5 is a view in elevation of the parts 45 shown in Fig. 4 taken on a plane at right angles thereto.

Fig. 6 is a detailed view showing the connections to the platform for moving the same in opposite directions.

50 Reference now being had to the details of the drawings by numerals,

1 designates a pier or dock and 2 a ship positioned adjacent thereto in readiness to be loaded. 3 designates a movable platform 55 or sled mounted on runners 4 and having on its upper surface longitudinally extending

upward projecting side flanges, or curbings, to prevent sidewise displacement of the barrels placed upon said sled, and a rear end flange, or curbing, the other end of said sled being open and unobstructed. 5 is a bail shaped member pivotally connected with the opposite sides of the platform and having an eye 6 to which a hook 7, fastened to a cable 8 is adapted to be connected. 60 Said cable passes over a pulley 9 fastened to a standard 10 rising from the deck of the ship and then winds about a drum 11 and thence over a pulley 13 secured to the standard 10 at a location above the point of attachment of the pulley 9 and thence extends to and is connected through the medium of a hook 15 with an eye 14 fastened to one 65 end of the platform. Said platform has near one end an upright member 16 to prevent barrels or other packages from rolling off when the platform is tilted.

A gang plank 18 bridges the space intermediate the pier and the side of the ship, and is disposed at an upward inclination 80 and up which gang plank the platform with its load is adapted to be hauled by the cable. A downward inclined platform 19 leads from the side of the ship at the end of the gang plank to the upper end of the hatchway 20 in which the conveyer is positioned. In operation, as the sled is drawn upward upon the gang plank 18, onto the downward inclined platform 19, it tilts downward, thus automatically dumping the barrels on the 85 sled, the barrels rolling off the open end of said sled. Said conveyer is made up preferably of hollow skeleton sections 21 preferably of metal and connected together in any suitable manner, any number of these sections being employed to reach different depths in the hold of the ship. Shock absorbers designated by numeral 21' and consisting of curved resilient bars are preferably positioned within the bottom section of 90 the conveyer and their lower ends are upwardly and inwardly curved as shown in the drawing. Screws 22 passing through the sides of this conveyer section and bearing against the upwardly curved portions of the 95 shock absorbers are provided for the purpose of regulating the tension of the latter.

Within the remaining section of the conveyer is preferably disposed a slightly modified form of shock absorber, comprising 100 curved resilient bars 21'', a pair thereof being disposed at each side of each of said 105

conveyer sections, one bar of said pair being disposed in a downwardly curved direction, and the other in an upwardly curved direction, said bars being secured at one end thereof to the conveyer section, and the free end of one of said bars being disposed in proximity to the other bar at a point substantially midway of the length thereof, so that when one bar is flexed by contact therewith of a barrel passing through the conveyer section, it will contact with the other bar, and the two bars will then be simultaneously flexed. Fastened to the lower portions of the conveyer are additional shock absorbers 23 formed of resilient bars of metal which are disposed at downward inclinations, and against which the barrels or other packages are adapted to contact to break gradually the fall thereof and down which inclined portions barrels are adapted to roll into the hold. When the drum is rotated in one direction the platform loaded with barrels, may be hauled up the inclined gang plank and down the inclined track 19, the barrels being prevented from rolling off the rear end of the platform by the standards thereon, and when the platform tilts down upon the inclined track 19 upon the deck of the boat, barrels will roll off the forward end of the platform without interference from the bail shaped member which will be raised out of the path of the barrels. As the barrels leave the platform they will roll into the upper end of the conveyer and fall down therein, their progress being arrested by their coming in contact with the various shock absorbers against which they contact as they pass down into the hold.

What I claim to be new is:

- 40 1. Apparatus for loading barrels from piers into the hold of a ship, consisting of a sectional conveyer, adapted to be disposed inside a ship and to extend into the hold thereof, said sections being superposed, means for conveying barrels to said conveyer for precipitating them therethrough, and shock absorbers carried by certain of said sections and comprising pairs of resilient curved bars, a pair thereof being disposed inside each of said conveyer sections, at each side thereof, one of said bars being disposed in a downwardly curved, and the other in an upwardly curved, direction, said bars being secured at one end thereof to said conveyer sections, and the free end of one of said bars in each pair being disposed in proximity to the other bar at a point substantially midway of the length thereof, whereby, when said downwardly curved bar is initially flexed by contact therewith of a barrel passing through the conveyer section, it will contact with the other bar, the two bars being thereupon simultaneously flexed, adjustably tensioned shock absorbers disposed within one of said conveyer sections, and comprising a resilient, downwardly curved bar disposed at each side thereof and having an upwardly projecting terminal, and means carried by said conveyer sections for regulating the tension of said adjustably tensioned shock absorbers.
- 45 2. Apparatus for loading barrels from piers into the hold of a ship, consisting of a

sectional conveyer, adapted to be disposed inside a ship and to extend into the hold thereof, said sections being superposed, means for conveying barrels to said conveyer for precipitating them therethrough, shock absorbers carried by certain of said sections, and comprising pairs of resilient curved bars, a pair thereof being disposed inside each of said conveyer sections, at each side thereof, one of said bars being disposed in a downwardly curved, and the other in an upwardly curved, direction, said bars being secured at one end thereof to said conveyer sections, and the free end of one of said bars in each pair being disposed in proximity to the other bar at a point substantially midway of the length thereof, whereby, when said downwardly curved bar is initially flexed by contact therewith of a barrel passing through the conveyer section, it will contact with the other bar, the two bars being thereupon simultaneously flexed, adjustably tensioned shock absorbers disposed within one of said conveyer sections, and comprising a resilient, downwardly curved bar disposed at each side thereof and having an upwardly projecting terminal, and means carried by said conveyer sections for regulating the tension of said adjustably tensioned shock absorbers.

3. Apparatus for loading barrels from piers into the hold of a ship, consisting of a sectional conveyer, adapted to be disposed inside a ship and to extend into the hold thereof, said sections being superposed, means for conveying barrels to said conveyer for precipitating them therethrough, shock absorbers carried by certain of said sections and comprising pairs of resilient curved bars, a pair thereof being disposed inside each of said conveyer sections, at each side thereof, one of said bars being disposed in a downwardly curved, and the other in an upwardly curved, direction, said bars being secured at one end thereof to said conveyer sections, and the free end of one of said bars in each pair being disposed in proximity to the other bar at a point substantially midway of the length thereof, whereby, when said downwardly curved bar is initially flexed by contact therewith of a barrel passing through the conveyer section, it will contact with the other bar, the two bars being thereupon simultaneously flexed, adjustably tensioned shock absorbers disposed within one of said conveyer sections, and comprising a resilient, downwardly curved bar disposed at each side thereof and having an upwardly projecting terminal, and means carried by said conveyer sections for regulating the tension of said adjustably tensioned shock absorbers.

4. Apparatus for loading barrels from piers into the hold of a ship, consisting of a

sectional conveyer, adapted to be disposed inside a ship and to extend into the hold thereof, said sections being superposed, means for conveying barrels to said conveyer 5 for precipitating them therethrough, shock absorbers carried by certain of said sections and comprising pairs of resilient curved bars, a pair thereof being disposed inside each of said conveyer sections, at each side 10 thereof, one of said bars being disposed in a downwardly curved, and the other in an upwardly curved, direction, said bars being secured at one end thereof to said conveyer sections, and the free end of one of said bars in 15 each pair being disposed in proximity to the

other bar at a point substantially midway of the length thereof, whereby, when said downwardly curved bar is initially flexed by contact therewith of a barrel passing through the conveyer section, it will contact 20 with the other bar, the two bars being thereupon simultaneously flexed, and downwardly inclined resilient bars carried exteriorly of the lowermost conveyer section for receiving the barrels issuing from said 25 conveyer.

In testimony whereof I hereunto affix my signature.

WILLIAM ELSWORTH JOHNSON.
